United States Patent Office

Des. 186,370
Patented Oct. 20, 1959

186,370

PICTURE CLIP

Ernest Russell, Eunice, La.

Application October 18, 1957, Serial No. 48,156

Term of patent 14 years

(Cl. D17—3)

Fig. 1 is a front perspective view of a picture clip showing my new design; and

Fig. 2 is a rear perspective view.

I claim:

The ornamental design for a picture clip, as shown.
